UNITED STATES PATENT OFFICE.

CHRISTEN CHRISTENSEN, OF CHICAGO, ILLINOIS, ASSIGNOR TO ELECTRICAL ENGINEERS EQUIPMENT COMPANY, OF CHICAGO, ILLINOIS, A CORPORATION OF ILLINOIS.

SWITCH.

Application filed November 20, 1920. Serial No. 425,825.

To all whom it may concern:

Be it known that I, CHRISTEN CHRISTENSEN, a citizen of the United States, residing at Chicago, in the county of Cook and State 5 of Illinois, have invented a certain new and useful Improvement in Switches, of which the following is a full, clear, concise, and exact description, reference being had to the accompanying drawings, forming a part of 10 this specification.

The present invention relates to switches, and embodies improvements upon the type of switch disclosed in my co-pending application, Serial No. 301,718, filed June 4, 1919, 15 which has resulted in Patent No. 1,394,968 of October 25, 1921, and in the co-pending application of Ernest H. Jacobs, Serial No. 381,235, filed May 14, 1920.

The present switch is particularly adapted 20 to outdoor work and it operates on the air-brake principle.

This means that the switch must be capable of withstanding weather conditions and the rough usage incidental to this type of 25 mechanism. The contacts are subject to greater wear and punishment than is the case of oil switches. In order to carry a heavy current large areas of contact must be provided and the parts become quite 30 heavy and are often difficult to start, because of the large static friction.

However, an air-brake switch should be operated rapidly to insure breaking of the arc as soon as possible.

35 The present type of mechanism is designed to meet these contradictory requirements.

In my co-pending application above referred to, I have disclosed a novel form of 40 switch operating mechanism comprising a series of links embodied in a closed polygonal figure and designed to impart a varying ratio of force and velocity to the switch blades in their actuating motion. The 45 theory of this variable ratio motion is to exert, during the initial opening motion of the switch blades, a powerful leverage of large force moment on the switch blades to overcome the static friction of the switch, 50 and to impart, during the remaining por-

tion of the throw, an accelerated, high speed motion to the switch blades so that a quick and positive break of the arc is assured. In the above mentioned co-pending application of Ernest H. Jacobs, this switch operating 55 mechanism has been shown as devised for the operation of double throw switches.

In the present invention I have disclosed a modified arrangement of this principle of switch operating mechanism, this arrangement being particularly designed for certain situations wherein a particular degree and character of switch opening motion is desired. More specifically, one of the objects of the invention is to provide a construction 60 of switch operating mechanism which will produce a maximum length of stroke of the switch blade in its switch opening motion. A further object is to provide a construction 65 of switch operating mechanism which will produce a constant or a continuously accelerating motion of the switch blade, at a relatively high velocity, from the moment the switch blade breaks contact with its contact terminal until it reaches the outer limit of 70 its arc-extinguishing throw. This increased stroke of the switch blade and the constant or continuously accelerating character of its motion are of particular advantage in that they tend to more quickly and effectively 75 quench the arc which is drawn. In this regard, they are of particular importance in double throw switches inasmuch as they afford greater assurance that in throwing the 80 movable switch element from one set contact terminals to the other the arc which is drawn from the first set of terminals will be completely extinguished before the movable switch element makes electrical connection with the other set of terminals. These 85 characteristics of greater throw of the switch blades and constant or continuously accelerating motion thereof are attained in the present arrangement of the links without reducing in any degree the leverage or mechanical advantage of the mechanism in the 90 opening actuation of the switch blades.

A further object in the present invention is to provide an improved construction of 95 high tension double throw switch in coop-

erative association with the above switch operating mechanism.

Referring to the accompanying drawings in which an illustrated embodiment of my invention is shown:

Figure 1 is a side elevational view of my improved switch;

Figure 2 is an enlarged elevational view of the same;

Figure 3 is an enlarged fragmentary view of the polygonal series of links; and

Figure 4 is a similar view of a modified arrangement of the links.

The switch illustrated is of the horizontal type of double throw switch, but it will of course be obvious that the invention has applicability to a vertical type of switch as well. The switch is of triple pole or three phase construction and is mounted upon three parallel channel irons 5 which are mounted horizontally on the pole or switching tower, or which may comprise part of the switching tower structure. The three individual units on the three channels 5 are identical in construction and operation, and I shall therefore describe only one of these units in detail.

Referring to Figure 1, at the ends of the channel 5 are supported vertical insulators 6 and 7 which have their bases mounted in insulator clamps 8 and 9 which are secured to mounting pedestals 10 and 11 on the channel member. Insulator clamps 12 and 13 are secured upon the upper ends of the insulators 6 and 7, and upon these clamps are supported the contact terminals 14 and 15. Referring particularly to the left hand terminal 14, each contact terminal comprises a horizontal plate 16 having an upstanding terminal lug 17, on each side of which is provided a guide member 18 for guiding the cooperating switch blade into position over the terminal 17. The outer end of the plate 16 is bent upwardly to support the inclined arcing horn 19. The ends of the transmission lines have connection with these contact terminals 14 and 15 through terminal connectors 22 which bolt to the plates 16.

Midway between the insulators 6 and 7 is mounted a central insulator 23, which has support in an insulator clamp 24 secured to a mounting pedestal 25, as described of the other insulators. The insulator clamp 26 on the upper end of the central insulator 23 supports the hinge terminal 27 to which are hinged the two switch blades 28 and 29. The blade 28 is arranged to contact only with its individual contact terminal 14 and the blade 29 with its individual terminal 15; as a result of which the angular throw required in swinging the movable switch element from one set of terminals to the other is considerably reduced. Each blade

28-29 is preferably built up of a pair of spaced blades which are trussed for greater strength and rigidity. The two lateral blades of the blade unit 28 have pivotal mounting between a pair of spaced pivot lugs constituting the upper end of the hinge terminal 27, and the two lateral blades of the blade unit 29 have concentric pivotal mounting with the blade unit 28 on the outside of these spaced pivot lugs. On the outer ends of the blades 28 and 29 are mounted sleet hoods 33, which are adapted to cooperate with the spaced lateral guide members 18 to surround and protect the contacting relation of the blade with the terminal lug 17 against sleet and other inclement weather. An arcing tip 34 is pivotally attached to the outer end of each sleet hood 33 for cooperation with the arcing horns 19; the arrangement being such that arcing only takes place between the arcing tip 34 and horn 19 so that there is no burning of the terminal lugs and blades. The outer end of each arcing tip 34 is conformed to embrace and have guiding engagement with its corresponding arcing horn while the switch blade is moving into position, the tip being yieldably pivoted so that it may fold upwardly into the position illustrated when the blade is in closed position.

The three poles of the switch are simultaneously operable from a point at the base of the switching tower or pole through the medium of an operating lever 36 which is pivoted in the slot of a forked bracket 37 mounted on the tower structure or pole. The lever 36 has pivotal connection to a vertical operating rod 38 through a link 39. The link 39 is curved in such a manner as to enable it to engage around the pivotal center of the operating lever 36 when the same is swung downwardly, whereby the operating lever may be swung through approximately 180 degrees of motion. In this manner the operating lever 36 is made self locking in either its upper or lower position by virtue of the fact that it revolves the pivotal connection with the rod 38 over center, i. e. into or past the vertical plane extending through the rod. The upper end of the operating rod 38 has pivotal connection through a link 41 with the end of an arm 42 which is rigidly mounted on a horizontal operating shaft 43. The shaft 43 extends transversely of the switch mechanism across the tops of the channels 5, and has bearing support in bearings 44 on these channels. Mounted upon the shaft 43, substantially in the plane of each pole unit of the switch are arms 45 which have pivotal connection with upwardly extending stems 46. Each stem 46 supports a separate operating insulator 47 for operating the movable switch

element of its individual pole. The insulator 47 has mechanical connection at its upper end with the improved link mechanism of its particular pole unit through an insulator clamp 48 which is provided with a projecting pivot lug 49. The improved link mechanism has pivotal connection with this pivot lug for operation thereby, in a manner which I shall now describe.

10 The link mechanism comprises a curved lever or arm 51 which is widened outwardly and slotted centrally as indicated at 52 to engage over the hinge terminal lug 27. The lever 51 is pivoted to this hinge terminal upon a pivot pin 53 which is extended through the hinge terminal and through the sides of the lever which embrace the terminal. It should be particularly noted that this pivot center 53 is situated below the pivot pin 50 on which the blades 28 and 29 are pivoted. The extending ends of the curved lever 51 form cooperating arms 54 and 57, one arm for each of the switch blades 28 and 29. The right-hand arm 54 of the lever 51 is formed with an upturned end 55 which is rounded and so positioned with respect to the switch blade 29 that it will be operable to engage said switch blade and function as a blade opening shoe in the initial motion of the link mechanism. The pivot lug 49 on the top of the insulator clamp 48 has pivotal connection with this right hand arm below the curved end 55 at the pivot 56. The left-hand arm 57 of the curved lever 51 is provided with a similarly upturned end 58 at substantially the same radius as the end 55, for engaging with the under side of the switch blade 28 for initiating its opening movement. The two blades 28 and 29 are rigidly connected together at the angle illustrated so as to form a unitary switch element by the provision of the diagonal strut or link 61, which is rigidly connected to the blades 28 and 29 at 62—62. Extending from the pivot pin 56 in the right-hand arm 54 is a link 64 which has its upper end pivotally connected to the diagonal link or strut at 65. Similarly, the left-hand arm 57 is provided with a pivot pin 66 at substantially the same radius as the pin 56, and from this pin extends a link 67 which also has pivotal connection with the diagonal strut 61 at the pivot point 65. When the switch blades 50 are in the position illustrated, the radial distance from the pivot 50 to the pivot 65 represents substantially the effective lever arm through which the arc extinguishing motion will be imparted to the switch blades, 60 and it should be particularly noted that, by reason of the raised position of the pivot 65 above the plane of the switch blade 29, this effective lever arm will either remain constant or diminish rather than increase 65 with the upward stroke of the switch blade.

Whether the effective lever arm will remain constant or will diminish will be dependent upon the position of the pivot 65 along the diagonal strut 61, as will be presently apparent.

70

I shall now describe the operation of the switch, making particular reference to Figure 3 to diagrammatically illustrate the action of the link mechanism. Upon swinging the operating lever 36 downward it will be apparent that the leverage of the lever 36 will be directly effective against the under side of the switch blade 29 through the engagement of the shoe end 55 therewith. During this part of the motion the lever arm 45 on the operating shaft 43 is operating through a comparatively short, powerful lever arm. Similarly, the leverage of the lever 36 is operating through a comparatively short, powerful lever arm. The maximum mechanical advantage of the operating mechanism is thus immediately effective during the initial part of the blade movement, and as a consequence the static friction and inertia of the movable switch element are easily overcome. It is only necessary that this maximum effort be exerted on the movable switch element during such time as the movable switch element is breaking frictional contact with the terminal lug, and during this part of the throw the multiplying action of the link mechanism is substantially non-effective, by reason of the slight play which will always exist between the pivoted links. If desired, additional play may be provided for by slotting certain of the pivot connections, such as at the pivot 65. It will be noted that the system of links for each of the switch blades defines a four-sided polygonal figure, as indicated by the dash and dot lines in Figure 3. In each of these polygonal figures, there are two moving pivots and two stationary pivots, the link mechanism having its swinging motion about these two stationary pivots. In the system of links for the right-hand side of the switch, the two pivots 50 and 53 correspond to the two stationary pivots of the figure, and the pivot pins 56 and 65 correspond to the two moving pivots. The portion of hinge terminal between the stationary pivots 50 and 53 corresponds to a stationary link *a*; the curved arm between the pivots 53 and 56 corresponds to a first toggle link *b*; the link 64 between the moving pivots 56 and 65 corresponds to a second toggle link *c*; and the radial line between the pivots 65 and 50 corresponds to a switch operating link or lever arm *r*. The pivot 65 moves through the arc *s*. As hereinbefore remarked, it is of particular note that the pivot 65 is located at an elevated point above the plane of the switch blade 29, in such position that when the switch blade is in closed position the lever arm *r* is

of approximately maximum effective length relative to the direction of thrust imparted by the link *c*.

As soon as the switch blade 29 has cleared the top of the contact terminal 17, the system of links becomes effective by imparting a high speed motion to the switch blade for the purpose of extinguishing the arc. This motion will follow from the fact that in the upward motion of the pivot 56, this pivot will—by reason of the eccentric disposal of the pivot 53 below the pivot 50—tend to swing inwardly toward the pivot 65. Thus an endwise thrust is imparted to the link *c*. To this is added the toggle motion incident in bringing the lower end of the link 64 up into more of a horizontal position, the two thrusting the pivot 65 to the left with a rapid motion of considerable amplitude. At the beginning of the arc extinguishing throw the pivot 65 is in position corresponding to substantially maximum length of lever arm *r*, with respect to this direction of endwise thrust from the link *c*. However, as the pivot 65 revolves to the left and down on the other side of the vertical center line, the effective lever arm through which the link *c* imparts its motion to the switch blades decreases to a slight extent. The present embodiment illustrates this decrease in lever arm as being comparatively small, and if desired, the position of the pivot 65 may be so adjusted as to maintain the effective lever arm substantially constant throughout the entire stroke of the switch blade. This question of having a decreasing or substantially constant lever arm is dependent upon certain conditions such as the desired stroke or throw of the switch, the weight of the movable switch element, the speed of throw, etc. These conditions may be met by the proper location of the pivotal centers of the inner ends of the links 64 and 67 along the strut 61. For example, if a more constant length of effective lever arm is desired for a substantially uniform velocity of arc-extinguishing throw this is obtained by pivotally mounting the inner ends of the links 64 and 67 on independent pivots which are spaced sufficiently apart along the strut 61 to maintain a substantially uniform length of lever arm between the limits of the throw. On the other hand, if a continuous, rapid decrease of lever arm is desired for a continuous, rapidly accelerating, arc-extinguishing throw, this is obtained by overlapping the ends of the links 64 and 67 and pivoting these ends at remote points along the strut 61, such as even at the points 62—62 as I shall presently describe. It is within the scope of my invention to so pivot the ends of these links as to obtain any of these desired characteristics of switch blade motion. Referring again to the operation of

the arrangement illustrated, it will be apparent that concurrently with the decrease in effective lever arm of the link or arm *r* the horizontal component of motion of the pivot 56 (represented in the entirety at *h*) continuously increases, and as a result of this increasing rate of motion of the link *c* and the decreasing length of effective lever arm through which it works on the switch blades, a continuously accelerating motion of the switch blades is obtained, this continuing until the blades are arrested by the blade 28 contacting with the terminal 14. This accelerated motion is also assisted by the increase in length of effective lever arm of the lever 45 as it moves upwardly, the increase of effective lever arm transmitting greater motion to the pivot 56. The continuously accelerating motion of the switch blade is of importance for quenching the arc in the briefest possible time, and is of particular importance in a double throw switch where it is essential that the arc from one set of terminals be entirely broken before contact is made with the other set of terminals. The arc interrupting action is also assisted by the large extent of blade opening which is secured by the present arrangement of the links. The location of the pivot 65 above the plane of the switch blade 29 and comparatively close to the pivot 50 permits of a relatively long link *c*, and the stroke of the blade is thus increased by the more effective toggle action of the links *b* and *c*. Referring again to the operation, when the multiplying motion of the links begins to accelerate the switch blade 29, the latter moves away from engagement with the switch opening shoe 55 so that the shoe 55 does not assist any further in the opening motion but merely trails the blade into open position, as illustrated of the shoe 58 and blade 28. As the one blade 29 moves into open position, the other blade 28 moves concurrently into closed position into contact with the contact terminal 14. The link mechanism for this side of the switch then assumes the relation just described of the right-hand link mechanism and upon the downward motion of the operating insulator 48 in making a return throw of the switch, this link mechanism on the left side of the switch will exert a large opening force on the switch blade 28 and will thereafter accelerate the arc interrupting throw of the switch blade 28 in the identical manner just described of the blade 29. It will be noted that the weight of each switch blade decreases as the blade rises to open position, and that the blades tend to balance each other to a certain extent. This assists the switch operating mechanism in producing the high speed motion above described. As I have hereinbefore stated, it is within

the scope of my invention to so pivot the ends of the links 64 and 67 at any desired point or points intermediate the blades along the strut 61, or beyond the blades if desired, as to obtain any desired characteristics of arc-extinguishing throw. In Figure 4 I have illustrated the links 64' and 67' as having their inner ends overlapped and pivotally connected to the pins 62-62. This arrangement is designed to give a rapidly decreasing length of effective lever arm with the result that the arc-extinguishing throw has a rapidly accelerating action. The initial effective lever arm at the beginning of the stroke is indicated at r' and at the end of the stroke is indicated at r'' . From this it will be seen that by the proper location of the pivots for the inner ends of the links 64 and 67 any desired action of lever arm may be obtained for any desired character of arc-extinguishing throw.

I do not intend to be limited to the details herein shown and described except as they are defined in the appended claims.

25 I claim:

1. In an electrical switch, the combination of contact terminals, a movable switch element, and switch operating mechanism comprising means exerting a relatively large force upon said movable switch element during the initial part of its motion, and a relatively large velocity during the remaining part of its motion, said switch operating mechanism imparting a high velocity motion 35 to said movable switch element through an effective lever arm of non-increasing length.

2. In an electrical switch, the combination of contact terminals, a movable switch element cooperating therewith, and switch operating mechanism comprising a series of links operating to exert an opening effort on said movable switch element of large force and small velocity and to impart an arc extinguishing motion of relatively high 45 velocity to said movable switch element after said opening motion, said series of links imparting said arc extinguishing motion to said movable switch element through a lever arm of non-increasing effective length.

50 3. In an electrical switch, the combination of contact terminals, a movable switch element, a switch operating member, means for imparting the operating motion of said member directly to said movable switch element during the initial motion of breaking contact, and a series of links connecting said switch operating member and said movable switch element, said series of links thereafter imparting a multiplied motion to said 55 movable switch element, said series of links imparting motion to said movable switch element through a lever arm of diminishing effective length for producing a continuously accelerating motion of said switch element.

60 4. In an electrical switch, the combina-

tion of contact terminals, a switch blade co-operating therewith, an operating member for moving said switch blade, and a plurality of links connecting said operating member with said switch blade, said series 70 of links comprising a first link connected to said operating member and having stationary pivotal support eccentric to the pivotal mounting of said switch blade, a second link pivotally connected at one end to said operating member, and means pivotally connecting the other end of said second link to said switch blades, said second link being pivoted to said connecting means at a point laterally of said switch blade.

5. In an electrical switch, the combination of a contact terminal, a switch blade co-operating therewith, a first stationary pivot about which said switch blade is adapted to swing, a second stationary pivot, a link 85 pivotally mounted thereon, a first moving pivot moving with said link, a second link pivotally mounted on said first moving pivot, a second moving pivot pivotally connecting said second link with said switch blade, operating means for actuating said links, said second moving pivot substantially defining the lever arm for transmitting motion to said switch blade, said second moving pivot being disposed whereby said lever arm 95 will decrease in effective length during opening motion of said switch blade.

6. In a double throw switch, the combination of a pair of contact terminals, an independent switch blade cooperating with each of said contact terminals, each of said switch blades having concentric pivotal mounting, said switch blades being rigidly connected together at an angle, switch operating mechanism comprising 100 means for exerting a relatively large effort upon said switch blades during the initial part of their opening motion and a relatively large velocity during the remaining part of their arc extinguishing motion, said switch 105 operating mechanism having operative connection with said switch blades at a point intermediate the two of said blades.

7. In a double throw switch, the combination of a pair of contact terminals, an intermediate hinge terminal, a pair of switch blades pivoted to said hinge terminal, a diagonal member rigidly connecting said blades together at an angle, a switch operating member adapted to exert a large 115 opening effort directly upon said switch blades in breaking contact with said contact terminals, link mechanism operatively connecting said switch operating member with said blades for multiplying the further motion of said switch operating member, said links comprising a first link pivoted eccentric to said switch blades and connected to said switch operating member, and a second link pivotally connected between said 120

- first link and said diagonal member between the switch blades.
8. In a double throw switch, the combination of a pair of contact terminals, an intermediate hinge terminal, a first stationary center in said hinge terminal, a pair of switch blades pivoted on said center, a diagonal member rigidly connecting said blades together at a V-angle, a second stationary center below said first stationary center, a lever pivoted centrally on said second stationary center, a pair of links each pivoted at one end to the ends of said lever, the other ends of said links having pivotal connection with said diagonal member between said switch blades, said lever comprising means adapted to engage directly with said switch blades for exerting a relatively large opening effort on said blades while breaking contact with said contact terminals, and a switch operating member for actuating said lever.
9. In an electrical switch, the combination of a contact terminal, a switch blade cooperable therewith, a stationary pivot terminal for said blade, linkage means for breaking contact of the blade with the contact terminal and swinging said blade into open position away from said terminal, said linkage means defining an arm of non-increasing radius operable about the stationary blade pivot to move the blade away from the contact terminal after contact is broken.
10. In an electrical switch, the combination of a pair of switch terminals, a pivoted switch blade operative to connect said terminals, a switch operating member adapted to apply a relatively slow powerful effort to the switch blade in the contact-breaking motion thereof, a link for transmitting an accelerated arc-extinguishing motion to said switch blade thereafter, a pivot swinging with said switch blade, said link being connected to said pivot at one end and having operative connection at the other end with said switch operating member, said pivot being disposed whereby the effective radius line from the pivotal center of said switch blade to the force line through said link is of non-increasing length.
11. In an electrical switch, the combination of a hinge terminal, a contact terminal, a switch blade pivoted on said hinge terminal for contact with said contact terminal, a switch operating member adapted to exert a relatively powerful opening force upon said switch blade during the contact-breaking motion thereof, means for transmitting an accelerated arc-extinguishing throw from said member to said switch blade after breaking contact, said means comprising a switch operating pivot swinging concentrically with said switch blade, a second pivot moving with said switch operating member, a link extending between said pivots, said switch operating pivot being disposed whereby the radius arm from the force line between said pivots to the pivotal center of said switch blade is of diminishing radius during a predetermined part of the arc-extinguishing throw.
12. In an electrical switch, the combination of a contact terminal, a blade cooperable therewith, a pivot for said blade, blade operating means including an arm pivoted eccentric to the blade pivot, and a pair of links pivoted to the blade and said arm, respectively, and to each other laterally of the blade.

In witness whereof I hereunto subscribe my name this 22nd day of October, 1920.

CHRISTEN CHRISTENSEN.
